UNITED STATES PATENT OFFICE.

HARLEY C. MOULTON, OF DORCHESTER, MASSACHUSETTS, ASSIGNOR, BY MESNE ASSIGNMENTS, TO LAWRENCE M. STEIN, OF CHICAGO, ILLINOIS.

WORK-PRESENTING MECHANISM FOR SEWING MACHINES.

Application filed October 20, 1919. Serial No. 332,025.

To all whom it may concern:

Be it known that I, HARLEY C. MOULTON, a citizen of the United States, and resident of Dorchester, county of Suffolk, State of Massachusetts, have invented an Improvement in Work-Presenting Mechanisms for Sewing Machines, of which the following description, in connection with the accompanying drawing, is a specification, like 10 characters on the drawing representing like parts.

This invention relates to improvements in work presenting mechanisms for sewing machines and the object thereof is to provide a sewing machine having an overhanging arm and head carrying stitch forming mechanism and feeding mechanism with a novel form of work support and bender mechanism adapted to co-operate with the 15 feeding mechanism in presenting the work to the stitch forming mechanism.

A further object of the invention is to provide a novel means of adjusting the bender mechanism, the regulation of which 20 may be accomplished conveniently by the operator from above the bed plate of the machine in which the adjusting means will be out of the way of work lying upon the bed plate of the machine. More specifically 25 the invention includes a bender actuating lever having an adjustable fulcrum by means of which the field of movement of the bender may be adjusted.

A further feature of the invention consists in providing a novel resilient connection between the bender engaging arm and the means for actuating said arm.

A further object of the invention is to provide a novel form of work support which 30 may be adjusted to position the bender in co-operative relation to the needle throat, foot and stitch forming mechanism.

Other objects and features of the invention will more fully appear from the following description and the accompanying drawings and will be particularly pointed out in the annexed claims.

The preferred embodiment of the invention is disclosed herein as applied to a sewing machine of the "Arbette" type for felling a superimposed layer upon a base layer of material but it will be understood that the invention may be embodied in other types of machines to which it may be applicable.

In the drawings:

Fig. 1 is a vertical median sectional view through the bed, standard and arm of a sewing machine embodying my invention, certain of the mechanisms being shown in 60 elevation,

Fig. 2 is an end elevation of the head end of the sewing machine,

Fig. 3 is an underneath plan view,

Fig. 4 is a detail vertical sectional view 65 through the work support, the bed plate being broken away and the bender actuating lever shown in elevation,

Fig. 5 is a detail transverse sectional view through the work support, and 70

Fig. 6 is a detail view of the mechanism for adjusting the fulcrum of the bender actuating lever, the bed plate being broken away.

The sewing machine illustrated in the accompanying drawings comprises a bed plate 1, preferably having adjacent one end an upwardly extending boss 2 forming a seat for the lower end of a vertical hollow standard 3 which is integral with an arm 80 4 extending over the bed plate and having at its end a head 5 which contains or supports the stitch forming mechanism and feeding mechanism hereinafter to be described.

The main shaft 6 is journaled in suitable bearings in the arm and standard and is actuated through a pulley 7 which desirably is rotatably mounted upon a sleeve 8 fixedly secured to one end of the shaft, the pulley 90 7 being releasably clamped to the sleeve by a nut 9 having a milled flange 10. Means are provided at the opposite end of the shaft 6 for actuating the stitch forming mechanism and the feeding mechanism.

The stitch forming mechanism comprises a curved oscillating needle 11 fixedly secured in the end of a needle bar 12 which is pivotally mounted upon a stud 13 extending across the bifurcated lower end of a bracket 14 which is adjustably secured to the lower end of a needle bar supporting lever 15, which preferably is journaled at its upper end upon a transverse shaft 16 extending across the head of the machine, preferably substantially in the plane of the line of stitching, whereby the lever may be shogged laterally to produce parallel rows of 100 105 stitches.

The opposite end of the needle bar 12 is 110

connected by a universal joint 17 to the lower end of a link 18 which is connected at its upper end by a universal joint 19 to the free end of a needle actuating lever 20 which is mounted at its opposite end upon an adjustable pivot secured to the head of the machine.

As illustrated in the accompanying drawings the end of the lever 20 is provided with 10 a boss 21 which is mounted on a pivot 22 having an eccentric stud 23 adjustably secured by a set screw, in a boss projecting from the inner wall of the head of the machine. The needle actuating lever 20 is connected intermediate of its ends to the upper end of a link 24, the lower end of which is pivotally mounted upon a stud 25 having a stem 26 fixedly secured in the end of the shaft 6 but eccentrically in respect to the 20 axis thereof.

By reason of this construction rotation of the main shaft 6 causes an oscillation of the needle actuating lever 20 about its pivotal support thereby reciprocating the link 18 25 and oscillating the needle bar and needle in the usual manner.

By reason of the adjustment of the pivotal end of the needle actuating lever 20 the stitching point, or point of entry of the 30 needle into the goods and point of emergence therefrom, may be varied and the needle also adjusted into proper co-operative relation to the complementary stitch forming mechanism.

35 The complementary stitch forming mechanism comprises a rotating loop taker or hook 27 carried at the lower end of a shaft 28 which is suitably journaled in the hook bracket 29 projecting downwardly from the lower portion of the head of the machine. A boss 30 extending upwardly within the head of the machine serves also as a bearing for the shaft 28. The upper end of the shaft 28 is provided with a gear 31 40 which meshes with a gear 32 fixedly secured upon the end of the driving shaft. The relation of the gears 31 and 32 desirably are two to one so that the revolving loop taker or hook will make two rotations to 45 every reciprocation of the needle as is usual in the "Arbette" type of machines.

In order to set the stitch which is formed by the co-operation of the needle and loop taker and to maintain proper timing relation between the parts, the take-up desirably 50 is driven from the same stud as that which actuates the needle mechanism. To this end the link 24 is provided with an offset extension 33 having at its end a stud 34 to 55 which the take-up actuating bar 35 is pivotally connected.

The bar 35 is slidably journaled in a suitable way in a block 36 which is pivotally mounted upon trunnions 37 in the arms of a 60 bracket 38, the lower ends of which are se-

cured to the upwardly projecting boss 30 in which the hook shaft 28 is mounted. The block 36 is provided with an extension or flange 39 to which the take-up 40 is secured by suitable screws.

It will therefore be obvious that the rotation of the stud 25, which is eccentrically of the main shaft 6, will cause the operation of the needle mechanism and also the take-up mechanism and that the movements of these mechanisms will be always maintained in proper timed relation.

Suitable means may be provided for vibrating the needle laterally to form two parallel lines of stitching such as are employed in felling, padding and overseaming. In the construction illustrated in the accompanying drawings this is accomplished by means of a pitman comprising a rod 41 having a reduced extension 42 extending through a suitable aperture in the needle bar supporting lever 15, a spring 43 surrounding the extension 42 being clamped between the needle bar supporting lever 15 and a nut 44 on said extension.

90 The pitman rod 41 is adjustably secured in the end of a member 45 having ways 46 and a cap 47 embracing a cam 48 upon a shaft 49 mounted transversely in the head of the machine, said shaft being operated by a gear 50 fixedly secured upon the hub of the cam 48 and engaging a complementary gear 51 upon the end portion of the main shaft 6.

In the operation of the machine the gear 51 which is secured upon the shaft 6, of course, rotates in unison with the needle actuating mechanism and through the gear 50 actuates the cam 46 to reciprocate the pitman 41. The shoulder on the pitman 41 formed by the reduction required to provide 100 the extension 42 abuts against the side of the needle bar supporting lever 15 and as the pitman is reciprocated in one direction serves to force the needle bar actuating lever laterally. As the pitman reciprocates in the opposite direction it reciprocates the needle bar actuating lever through the action of the nut 44 on the extension 42 upon the spring 43. By adjusting the pitman rod 41 in its socket in the member 45 the field of 105 lateral vibration of the needle may be varied while by clamping the needle bar supporting lever against movement in its extreme outward position (toward the left), the vibratory action of the pitman on said lever may be eliminated since the spring 43 will, by compression, permit the reciprocation of the pitman without actuating the needle bar supporting lever while, during the reciprocation of the pitman in the other 110 direction the extension will play freely 115 through the aperture in said lever.

120 Any suitable means may be provided for locking the needle bar supporting lever. A 125 convenient means which is disclosed herein 130

comprises a set screw 52 seated in the front wall of the lower portion of the head of the sewing machine and having its end positioned to engage the side of a cross head on the needle bar supporting lever 15 which is guided in suitable ways in the lower portion of the head.

By reason of this construction the machine is adapted to be operated either to form two parallel lines of stitching such as are employed in blind stitching or to produce straightaway blind stitching.

The sewing machine is provided with a rigid presser foot which is carried by the hook bracket. The work is presented to the stitch forming mechanism by feeding mechanism which is carried by the head of the sewing machine and operated by mechanism mounted in said head.

The feed dog thus carried by the head of the sewing machine co-operates with a yieldable work support to advance the work for the successive stitches. The base layer is presented in the path of the needle by a bender which is thrust through the work support a sufficient distance to bend it upwardly into the path of the oscillating needle. By thus providing an upper feeding mechanism all the difficulty which heretofore has been encountered by reason of the bender interfering with the proper feeding of the goods is eliminated.

The present application is addressed more particularly to the novel work supporting means and bender mechanism as will herein-after more fully appear.

The work support comprises a work supporting plate 53 which is fixedly secured upon the upper end of a hollow stem 54 which is slidably mounted in a tubular standard 55 which is fixedly secured to an arm 57 at the lower end of a bracket 58 which is secured to the under surface of the bed 1 by suitable screws 59, one of which passes through a slot 59* in the bracket 58 thereby providing means for adjusting the tubular standard and consequently the bender forward or backward in the line of stitching, so that it may be properly positioned in relation to the needle for different widths of needle throat required for different kinds of work. A guide, embracing said standard, which is slidably mounted in said bed to permit movement of the standard and bender to adjusted positions along the line of stitching, serves to prevent lateral vibration of said standard and the bender which is supported by it. The hollow stem 54 is provided with opposite guide slots 60 which receive the cylindrical ends of screws 61 which are seated in the wall of the standard 55. The work support 53 is normally sustained in extended position to co-operate with the presser foot 62 by a helical spring 63 which

bears upon the under wall 64 of the work support and at its lower end is seated upon a bender guiding support 65 which is conveniently secured in place by screws 66 having conical ends entering corresponding sockets in the walls of the support 65.

The tubular stand 55 is normally held in elevated position by a member 67 which is secured to said tubular member and is provided with a hollow boss 68 which receives the upper end of a helical spring 69, the lower end of which is seated in a socket in an adjusting screw 70 in the lower arm 57 of the bracket 58.

The boss 68 is provided with a flat guiding surface 71 which engages an adjustable guideway preferably in the form of a wedge shaped member 72 the inclined face of which engages the correspondingly inclined face of the vertical wall of the bracket 58, the wedge shaped adjusting member 72 being suitably secured in position by screws 73 (see Fig. 5).

Means are provided for depressing the stand and work support to permit the introduction and removal of the work. A convenient mechanism for accomplishing this purpose comprises a lever 74 which is pivoted at its outer end upon a stud 75 secured to the bracket 58 and rests upon a rib 76 which extends transversely across the top of the boss 68. The opposite end of the lever 74 is engaged by the end of an arm 77 of a rock shaft 78 to which a knee lever 79 is pivotally secured. Suitable set screws 80 and 81 projecting through the arm 77 and an extension thereof serve to limit the movement of the arm which is actuated by the knee lever.

By reason of this construction the operator by pressing the knee upon the lever 79 can depress the stand 55 and work support to any desired distance for the purpose of introducing or removing the work from stitching position.

The bender mechanism comprises a bender 82 preferably having a V-shaped work engaging end 83 and an enlarged stem 84 which is reciprocably journaled in the guide 65. The lower end of the bender is connected to a cross head 85 having a central slot 86 through which to receive the cylindrical end of a bender actuating arm 88 which is rotatably mounted upon a rock shaft 89.

The arm 88 is provided with an extension 90 which extends parallel to and engages an arm 91 having a collar 92 rigidly secured to the rock shaft 89. In order to provide for a yielding movement of the bender when an obstruction is encountered during its actuation yieldable means are provided for connecting the arms 90 and 91 together. A convenient means comprises a rod 93 fixedly secured to the arm 90 and extending through

an aperture in the arm 91 and provided with a helical spring 94 surrounding it which may be compressed to any desired amount by a nut 95 adjustably secured upon the rod 93.

In order to prevent jumping of the bender and to take up any wear which may occur a rod 96 attached to the cross head 85 extends through an aperture in the plate 97 and is provided with a spring 98 abutting at its upper end against the plate 97 and secured upon said rod by suitable nuts 99. By this construction the crosshead 85 is always maintained in proper engagement with its actuating arm 88 and the proper operation of the bender insured.

The rock shaft 89 is journalled in suitable bosses 100 and 101 extending downwardly from the lower face of the bed plate and is provided at its end with an arm 102 which is connected by a universal joint 103 to the end of a bender actuating lever 104 which has at its opposite end a fork 105 embracing the bender actuating cam 106.

The bender actuating cam 106 is secured to the end of a vertical shaft 107 which is journalled in suitable bearings 108 and 109 in the boss 2 which forms a part of the bed of the machine. An arm 110 which is secured to the upper end of the shaft 107 is connected by a link 111 to an arm 112 of a shaft 113 which is axially out of alinement with the shaft 107 so that the rotation of the shaft 113 will impart a variable rotative movement to the shaft 107. The shaft 113 is journalled in suitable bearings in webs 114 and 115 extending across the standard 3 of the sewing machine and is provided at its upper end with a mitre gear 116 which engages a complementary mitre gear 117 upon the main shaft of the machine. The gear 116 desirably is twice the diameter of the gear 117 thereby causing one reciprocation of the bender upon every second rotation of the main shaft. Inasmuch as the needle is reciprocated upon every rotation of the main shaft the bender will be elevated upon alternate reciprocations of the needle, thereby providing means for presenting the base layer in the path of the needle for every other stitch, the intermediate stitches being made in the superimposed layer as is common in felling machines of the Arbeiter type. It will be understood however, that by substituting gears of equal diameter for the gears 116 and 117 the bender may be caused to reciprocate upon each revolution of the main shaft and consequently in unison with each oscillation of the needle. Thus the machine may be adapted for padding or for straightaway stitching or for other purposes.

It will be noted that the variable movement imparted to the shaft 107 by reason of the linkage between the shaft 113 and the shaft 107 will cause the cam 106 to have

a movement which will produce a longer dwell in its action upon the fork of the bender actuating lever 105 than should be produced by the configuration of the cam itself. Thus the bender may be given a very rapid reciprocation with prolonged periods of dwell at the time the needle is entering and emerging from the work and also when the bender is depressed and the feeding operation being accomplished. Thus interference with the free feeding movement of the goods is avoided.

It is desirable that means shall be provided for varying the amplitude of reciprocation of the bender to enable it properly to present work of different thickness to the needle. The present invention contemplates a novel adjusting mechanism which will permit a very accurate regulation of the field of reciprocation of the bender and which will be so removed from the stitch forming mechanism as not to interfere with manipulation of the work. This is accomplished by providing means for adjusting the fulcrum of the bender actuating lever.

In the preferred construction illustrated in the accompanying drawings the bender actuating lever 104 is provided centrally with a boss 118 provided with a journal which is mounted upon a stud 119 which projects eccentrically from the end of a supporting shaft 120 which preferably is journalled in a split bearing 121 in a bracket 122 which is secured to the under surface of the bed plate by screws 123. A collar 124 fixed to the upper end of the shaft 120 and resting upon the upper end of the bearing 121 serves to support the shaft 120, and nuts 125 upon the end of the extension 119 to support the bender actuating lever 104.

The collar 124 is provided with an arm 126 which projects through a slot 127 in the side of the boss 2 and is provided with a handle 128 by means of which it may conveniently be adjusted. An index 129 secured to the lower face of the lever 126 and passing over a dial 130 on the bed plate serves to indicate the adjustment of the shaft which forms the fulcrum for the bender actuating lever 104. The index 129 may be provided with a projection 131 adapted to engage the serrated edge 132 of a plate 133 secured to the base plate of the machine, the engagement between the projection 131 and said serrated edge 132 serving to retain the lever 126 in adjusted position.

It will be apparent that by rotarily adjusting the shaft 120 in the manner above described the position of the stud 119 which forms the fulcrum of the bender actuating lever 104 may be varied, thus varying the position of the arm 102 of the rock shaft, thereby causing the bender actuating arm 88 to be raised or lowered as the case may be so that the field of reciprocation of the

bender may be varied without substantially changing the amplitude of its reciprocation, or substantially modifying the timing of its movement with respect to the stitch forming mechanism.

It will be understood that the embodiment of the invention disclosed herein is illustrative and not restrictive and that various changes in construction and arrangement of parts may be made within the spirit and scope of the following claims.

Having thus described my invention what I claim as new and desire to secure by Letters Patent is:

15 1. Work presenting mechanism for sewing machines comprising a bender, a bender actuating lever having a journal, a pivotal support therefor having an eccentric stud engaging the journal on said lever, means for rotarily adjusting said stud and means for oscillating said bender actuating lever.

20 2. Work presenting mechanism for sewing machines comprising a bender, a bender actuating lever having a journal, a pivotal support therefor having an eccentric stud engaging the journal on said lever, means for rotarily adjusting said stud, including an arm having an index and a co-operating scale graduated to indicate the position of said adjustment and means for oscillating said bender actuating lever.

25 3. Work presenting mechanism for sewing machines comprising a bender, a bender actuating lever having a journal, a pivotal support therefor having an eccentric stud engaging the journal on said lever, means for rotarily adjusting said stud, including an arm having an index, a co-operating scale graduated to indicate the position of said adjustment and locking means for securing said arm in adjusted position and means for oscillating said bender actuating lever.

40 4. Work presenting mechanism for sewing machines comprising a bender, a bender actuating lever having a cam fork and a journal, a pivotal support therefor having an eccentric stud engaging the journal on said lever, means for rotarily adjusting said stud, a bender actuating cam within said cam fork and means for rotating said cam.

45 5. Work presenting mechanism for sewing machines comprising a bender, a bender actuating lever having a cam fork and a journal, a pivotal support therefor having an eccentric stud engaging the journal on said lever, means for rotarily adjusting said stud, a bender actuating cam within said cam fork and means for imparting a variable speed of rotation to said bender actuating cam.

50 6. Work presenting mechanism for sewing machines comprising a reciprocable bender, a rock shaft having an arm directly engaging said bender, a lever connected to said rock shaft having an adjustable fulcrum, means

for adjusting said fulcrum and means for actuating said lever.

65 7. In a sewing machine comprising a bed, a work support, a bender reciprocably mounted in said work support, a rock shaft below said bed having an arm directly engaging said bender, a bender actuating lever connected to said rock shaft, an adjustable fulcrum for said bender actuating lever, means for adjusting said fulcrum and means for actuating said lever.

70 8. In a sewing machine comprising a bed, a work support, a bender reciprocably mounted in said work support, a rock shaft below said bed having an arm connected to said bender, a bender actuating lever connected to said rock shaft, a bracket connected to said bed having a bearing, a shaft rotatably mounted in said bearing, an eccentric stud on said shaft, a bender actuating lever fulcrumed on said stud and connected to said rock shaft, means for oscillating said lever and means for rotarily adjusting said shaft to vary the position of the fulcrum of said bender actuating lever.

75 9. In a sewing machine comprising a bed, a work support, a bender reciprocably mounted in said work support, a rock shaft below said bed having an arm connected to said bender, a bender actuating lever connected to said rock shaft, a bracket connected to said bed having a split bearing, a shaft rotatably mounted in said bearing, means for adjustably clamping said bearing upon said shaft, an eccentric stud on said shaft, a bender actuating lever fulcrumed on said stud and connected to said rock shaft, means for oscillating said lever and means for rotarily adjusting said shaft to vary the position of the fulcrum of said bender actuating lever.

80 10. In a sewing machine comprising a bed plate having an upwardly extending hollow boss having a slotted wall, a standard having an overhanging arm mounted on said boss, a bracket mounted within said boss having a vertical bearing, a shaft rotatably mounted in said bearing having an eccentric stud, a bender, a bender actuating lever mounted on said stud, means connecting said lever to said bender, a supporting collar fixed on said shaft having an arm extending through the slotted wall in said boss, means for securing said arm in adjusted positions, and means for oscillating said bender actuating lever.

85 11. In a sewing machine comprising a bed, a hollow vertical standard rising therefrom carrying an overhanging arm and head, a main shaft journalled in said arm, a work support and a bender reciprocably mounted in said work support, means for actuating said bender including a horizontal bender actuating lever, a vertical shaft mounted in

- said hollow standard having a cam engaging said bender actuating lever and means for rotating said vertical shaft from said main shaft.
12. In a sewing machine comprising a bed, a hollow vertical standard rising therefrom carrying an overhanging arm and head, a main shaft journaled in said arm, a work support and a bender reciprocably mounted 10 in said work support, means for actuating said bender including a horizontal bender actuating lever, a vertical divided shaft having upper and lower sections out of axial alignment mounted in said hollow standard and bed, means for rotating the upper section of said vertical shaft from said main shaft, means connecting said shaft sections to impart a variable rotary movement to the lower section and a cam on said lower shaft 20 engaging said bender actuating lever.
13. In a sewing machine comprising a bed, a work support having a standard extending through said bed and a bender reciprocably mounted in said standard, means for actuating said bender including an oscillating rock shaft having an arm rigid therewith, a bender engaging lever rotatably mounted on said rock shaft, resilient means connecting said arm and said lever capable of permitting 25 a yielding movement therebetween when the bender is subjected to pressure in excess of a predetermined amount.
14. In a sewing machine comprising a bed, a work support having a standard extending through said bed and means for depressing said standard, a bender reciprocably mounted in said standard, means for actuating said bender including resilient means capable of permitting said bender to 35 yield when subjected to pressure in excess of a predetermined amount and a spring connected to said bender acting to take up wear and to maintain the bender in proper operative position.
15. In a sewing machine comprising a bed, a work support having a tubular standard extending through said bed plate, yieldable means supporting said standard and means for depressing said standard, a bender having a crosshead reciprocably mounted in 45 said standard, means for actuating said bender including a yieldable arm engaging said cross head, a spring mounted in said standard connected to said cross head capable of yielding under the normal action of said bender actuating means and acting to take up wear and maintain the bender in proper operative position.
16. In a sewing machine comprising a bed, 60 a bracket depending therefrom and a work support having a standard slidably mounted in said work support and bracket; a member rigidly secured to said standard, a spring on said bracket supporting said member, a guide 65 means for depressing said member, a guide on said bracket engaging said member and means for adjusting said guide.
17. In a sewing machine comprising a bed, a bracket depending therefrom and a work support having a standard slidably mounted 70 in journals in said bracket; a member rigidly secured to said standard, a spring on said bracket supporting said member, means for depressing said member, a guide on said bracket engaging said member and 75 means for adjusting said guide comprising a wedge shaped plate having a guiding surface engaging said member and a surface disposed in angular relation thereto engaging said bracket with means for securing 80 said plate in adjusted position.
18. In a sewing machine comprising a bed, a tubular standard for a work support extending through said bed, a work support having a hollow stem slidably mounted in 85 the upper end of said standard, a bender guide in said standard, a spring seated on said bender guide yieldably supporting said work support, a bender reciprocably mounted in said bender guide and means for reciprocating said bender.
19. In a sewing machine comprising a bed, a tubular standard for a work support extending through said bed, a work support having a hollow stem slidably mounted in 90 the upper end of said standard, a bender guide in said standard, a spring seated on said bender guide yieldably supporting said work support, a bender reciprocably mounted in said bender guide, means for actuating 95 said bender, and a spring in the lower end of said standard normally acting to hold said bender in engagement with said bender actuating means.
20. In a sewing machine comprising a bed, 100 a tubular standard for a work support extending through said bed, a work support having a hollow stem slidably mounted in the upper end of said standard, a bender guide in said standard, a spring seated on 105 said bender guide yieldably supporting said work support, a crosshead in said standard connected to said bender, means including an arm for reciprocating said crosshead and a spring connected to said crosshead located 110 in the lower portion of said standard acting normally to hold said crosshead in engagement with the means.
21. In a sewing machine comprising an overhanging arm and head, a curved oscillating needle and complementary stitch forming mechanism carried by said head, work presenting mechanism including a bender and means for actuating the same to co-operate with said needle, means for adjusting 115 said bender relatively to said stitch forming mechanism in the general direction of the line of feed.
22. In a sewing machine comprising a bed, 120 an overhanging arm and head, a curved 125

oscillating needle and complementary stitch forming mechanism and feeding mechanism carried by said head; a bender, means for actuating same to co-operate with said needle and means for adjusting said bender relatively to said stitch forming mechanism in the general direction of the line of feed.

23. In a sewing machine comprising a bed, an overhanging arm and head, a curved oscillating needle and complementary stitch forming mechanism carried by said head, a bracket depending from said bed, a bender carried by said bracket and means for adjusting said bracket to vary the position of the bender relatively to the stitch forming

mechanism and means for actuating said bender.

24. In a sewing machine comprising a bed, an overhanging arm and head, a curved oscillating needle and complementary stitch forming mechanism carried by said head, a bracket pivotally connected to the under side of said bed, a bender carried by said bracket means for adjusting said bracket about its pivot to vary the position of the bender in the general direction of the line of stitching and means for actuating said bender.

In testimony whereof, I have signed my name to this specification.

HARLEY C. MOULTON.
